United States Patent Office.

CHARLES L. W. BAKER, OF HARTFORD, CONNECTICUT.

Design No. 3,767, dated November 30, 1869.

DESIGN FOR A BRUSH.

The Schedule referred to in these Letters Patent and making part of the same

To all whom it may concern:

Be it known that I, CHARLES L. W. BAKER, of the city and county of Hartford, and State of Connecticut, have invented or produced a new and original Design for Cleaning-Brush; and to enable others to understand and construct the same, I will proceed to describe, by referring to the drawings, in which the same letters indicate like parts in the figures.

a is the brush material.

b is the wood or stock.

c is the holding-device.

d is a tightening-nut.

e is a screw-shank and handle-socket.

f is a handle.

The whole is combined to produce a new and useful design for a cleaning-brush.

What I claim, and desire to secure by Letter Patent, is—

The design for a cleaning-brush, substantially as shown and described.

CHS. L. W. BAKER. [L. S.]
